UNITED STATES PATENT OFFICE.

WILLIAM J. STENGER, OF MOHALL, NORTH DAKOTA.

WRENCH.

No. 909,474.

Specification of Letters Patent.

Patented Jan. 12, 1909.

Application filed July 27, 1908. Serial No. 445,555.

To all whom it may concern:

Be it known that I, WILLIAM J. STENGER, a citizen of the United States, residing at Mohall, in the county of Ward and State of North Dakota, have invented a new and useful Wrench, of which the following is a specification.

This invention relates to wrenches of the adjustable jaw type.

10 The objects of the invention are, the provision in a merchantable form, of a device of the above-mentioned class, which shall be inexpensive to manufacture, facile in operation and devoid of complicated parts; a device which may be adjusted rapidly to grasp nuts and bolt-heads of different sizes; a device which shall hold securely the parts which it is the office of the wrench to seize and turn.

20 With these and other objects in view, as will hereinafter more fully appear, the invention consists in the novel construction and arrangement of parts hereinafter described, delineated in the accompanying drawings and particularly pointed out in the appended 25 claims, it being understood that divers changes in the form, proportions, size and minor details of the structure may be made without departing from the spirit or sacrificing any of the advantages of the invention.

Similar numerals of reference are employed to indicate corresponding parts throughout the several figures of the drawings.

30 In the accompanying drawings, Figure 1 is a longitudinal section of the complete device, in a plane passed along the side of the shank 1; Fig. 2 shows my invention in longitudinal section, the sectional plane in the upper portion of the figure being passed along the rear face of the shank 1 to a point a short distance above the handle 20, and thence, in the lower portion of the figure, passed through the axes of the openings in which are mounted the rivets 14 and 16, the various rivets disposed in the sectional planes being shown in elevation. Fig. 3 is a detail perspective showing the movable jaw 5 and the spring 6; Fig. 4 is a transverse section through the handle 20.

35 In the following description, I have designated the end of the wrench to which the fixed jaw 2 is attached, as the upper end, and the side of the wrench which is placed against the nut to be turned, as the front of the device.

50 In carrying out my invention, I provide a

handle 20 and shank 1, which in its preferred form is rectangular in transverse section. To the upper end of the shank 1 is removably attached the fixed jaw 2. The attachment of the fixed jaw 2 to the shank 1 may be effected variously; in the form shown, a rivet 3 is passed through the fixed jaw 2, registering with a slot 4 in the rear of the shank 1.

55 The movable jaw 5 is provided with a central opening 21 adapted to receive the shank 1, the said opening being slightly larger than the transverse section of the shank 1, allowing the movable jaw 5 a slight pivotal movement upon the shank 1. It will be seen that the construction last above described will permit the diagonally opposite edges of the central opening in the movable jaw 5 to engage the shank 1 with a clamping effect.

60 Embracing the shank 1 is the U shaped spring 6, having its ends attached rigidly to the front of the movable jaw 5. The securing of the ends of the U shaped spring 6 is a matter of mere mechanical skill. I prefer to 65 retain them by the plate 7 which may be forced into clamping effect upon the said spring-ends by the screw 8, engaging a threaded opening in the lower surface of the movable jaw 5. The spring 6 is the member 70 of my device which is subject to the most rapid deterioration of any of the component parts, and the use of the plate 7 and the screw 8 furnishes a means whereby a worn out or tired spring may be replaced quickly 75 with a new one.

75 The spring 6 is bent downward at an angle to the lower face of the movable jaw 5, bringing the rear portion 9 into contact with the rear of the shank 1, the effect of the contact being to maintain diagonally opposite edges of the central opening 21 in the movable jaw 5, in contact with the shank 1. I prefer to fashion the shank 1 without notches, and the movable jaw 5 may, therefore, be 80 slid readily upward, engaging between itself and the fixed jaw 2, the nut or bolt-head which is to be turned. The spring 6 maintains the movable jaw 5 in an operative position, as heretofore described, and when torsion is applied to the object to be rotated, the slight grip of the diagonally opposite edges of the central opening 21 in the movable jaw 5 upon the shank 1, secured by the action of the spring 6, will be increased to a positive 85 grip.

90 The handle of my wrench comprises the

parallel handle-pieces 10, which are spaced apart. Shoulders 11 connect these handle-pieces 10 with the shank 1, and a **V** shaped butt-piece 12 unites their lower ends. In practice, the shank 1, handle-pieces 10, shoulders 11 and butt-piece 12 may be made integral; and this method of construction I prefer, a ferrule 13, having a central opening adapted to engage the shank 1 and the shoulders 11 may be attached to the device by a rivet 14, or similar means, and over the **V** shaped butt-piece 12 may be placed the cap 15, secured in its place by the rivet 16. The ferrule 13 is of solid construction and serves to reinforce the shank 1 against bending under the violent strains to which tools of the wrench type are subjected.

Mounted upon the handle-pieces 10 are the oppositely disposed grips 17, their ends abutting against, and terminated longitudinally by, the ferrule 13 and the cap 15. From the inner surfaces of the grips 17, and integral therewith, project the blocks 18, adapted to engage the openings between the handle-pieces 10, forming a rigid and durable handle. The grips 17 may be held in place by any of the conventional methods of the craft; I have shown the rivets 19 as adapted to that end.

It will be noticed that the butt-piece 12 is **V** shaped and that the cap 15 is provided with a central opening adapted to engage the apex of the **V** shaped butt-piece. The butt of a wrench is not infrequently subjected to violent shocks, and by the construction shown, the cap 15 is prevented from being shoved upward, and the cracking or breaking of the grips 17 obviated.

In assembling the wrench, the end of the shank 1 is passed through the ferrule 13 and the ferrule slid downward into bearing with the shoulders 11 and there secured. The movable jaw 5 is mounted upon the shank 1, and finally, the fixed jaw 2 is secured to the top of the shank 1.

Having thus described my invention, my claims are as follows:

1. In a device of the class described, a shank; slidably mounted upon the shank, a movable jaw having a central opening arranged to receive the shank; a plate arranged to be clamped to the front of the movable jaw; a **U**-shaped spring having its ends secured between the plate and the jaw, the said spring being bent downward at an angle to the lower face of the movable jaw into contact with the rear of the shank.

2. In a device of the class described, a shank; a fixed jaw removably mounted upon the shank; parallel handle pieces, spaced apart; shoulders uniting the handle pieces with the shank; a **V**-shaped butt piece uniting the ends of the handle pieces; the said shank, handle pieces, shoulders and butt

piece being formed integrally; a ferrule 65 embracing the shank and the shoulders, and having a central opening adapted to engage said shank and shoulders; a cap covering the butt piece; oppositely disposed grips mounted upon the handle pieces and terminated longitudinally by the ferrule and the cap; blocks projecting inwardly from the grips and integral therewith, and adapted to register with the space between the handle pieces.

3. In a device of the class described, a 75 shank; a fixed jaw removably mounted upon the shank; a movable jaw slidably mounted upon the shank; parallel handle pieces spaced apart; shoulders uniting the handle pieces with the shank; a **V**-shaped butt- 80 piece uniting the ends of the handle pieces; the said shank, handle pieces, shoulders and butt-piece being formed integrally; a ferrule embracing the shank and the shoulders, and having a central opening adapted to engage 85 said shank and shoulder; a cap covering the butt-piece; oppositely disposed grips mounted upon the handle pieces and terminated longitudinally by the ferrule and the cap; blocks projecting inwardly from the grips 90 and integral therewith, and adapted to register with the space between the handle pieces.

4. In a device of the class described, a shank; parallel handle pieces spaced apart; 95 shoulders uniting the handle pieces with the shank; a **V**-shaped butt-piece uniting the ends of the handle pieces; the said shank, handle pieces, shoulders and butt-piece being formed integrally; a ferrule embracing the shank and the shoulders, and having a central opening adapted to engage said shank 100 and shoulders; a cap covering the butt-piece; oppositely disposed grips mounted upon the handle pieces and terminated longitudinally 105 by the ferrule and the cap; blocks projecting inwardly from the grips and integral therewith, and adapted to register with the space between the handle pieces.

5. In a device of the class described, a 110 shank; mounted upon the shank, a movable jaw having a central opening arranged to receive the shank and larger than the transverse section of the shank; a **U** shaped spring having its ends secured to the front of the 115 movable jaw, the said spring being bent downward at an angle to the lower face of the movable jaw into contact with the rear of the shank and arranged to hold diagonally opposite edges of the opening in the movable 120 jaw in contact with the shank.

6. In a device of the class described, a shank; mounted upon the shank, a movable jaw having a central opening arranged to receive the shank and larger than the transverse section of the shank; a plate arranged to be clamped to the front of the movable 125 jaw; a **U** shaped spring having its ends se-

cured between the plate and the jaw, the said spring being bent downward at an angle to the lower face of the movable jaw into contact with the rear of the shank and arranged to hold diagonally opposite edges of the opening in the movable jaw in contact with the shank.

In testimony that I claim the foregoing as my own, I have hereto affixed my signature in the presence of two witnesses.

WILLIAM J. STENGER.
